Baldwin Hale Attorney.

UNITED STATES PATENT OFFICE.

BENJAMIN HOLT, OF STOCKTON, CALIFORNIA.

RADIATOR.

1,143,967.

Specification of Letters Patent. Patented June 22, 1915.

Application filed October 14, 1911. Serial No. 654,735.

To all whom it may concern:

Be it known that I, BENJAMIN HOLT, a citizen of the United States, and residing at Stockton, in the county of San Joaquin, State of California, and whose post-office address is care of The Holt Manufacturing Company, at the same place, have invented certain new and useful Improvements in Radiators; and I do hereby declare the following to be a full, clear, and exact description of the said invention, such as will enable others skilled in the art to which it most nearly appertains to make, use, and practise the same.

This invention relates to improvements in radiators for the cooling systems of internal combustion engines.

The invention consists of the novel construction and arrangement of the parts, and of the novel method of circulating the cooling medium, as hereinafter more fully set forth.

The objects sought to be accomplished are the production of a radiator mechanically simple, easily assembled and repaired; combined with a circulating system wherein the cooling medium at its lowest temperature is circulated about the combustion chambers, wherein the temperature is the highest.

Broadly the invention consists of a radiator comprising upper and lower headers, with lateral openings, tubular manifolds hermetically sealed in said openings and having a tiebolt, extending therethrough whereby the manifolds are held in position on the headers; a series of radiation tubes communicating between the upper and lower manifolds and hermetically fixed therein. The upper and lower headers are divided into chambers, whereby the circulating medium discharged into the header, passes into the first set of manifolds, down through the radiation tubes into the lower manifolds and into the lower header; from whence it is distributed to the second set of manifolds and passes upward through the radiation tubes, to the second manifold, communicating with the top header, where it is distributed to the third set of manifolds, and so continuing downward and upward until discharged from the upper manifolds and passed back to the reservoir from whence it is pumped directly to the engine cylinders, from whence it is discharged into the radiator, as described. In the radiator the cooling medium is subjected to a blast from a mechanically

driven fan located in front of the radiator, and adapted to force air around and about the radiation tubes.

In the drawings: Figure —1— is a diagrammatic side elevation of this invention as applied to an internal combustion engine. Fig. —2— is a plan view from above of the radiator. Fig. —3— is a vertical cross section taken longitudinally of the top header. Fig. —4— is a similar view of the lower header.

In detail the construction consists of the upper header 1, having the threaded inlet opening 2, and the chamber 3, with the lateral openings 4, having a concentric annular groove, adapted to receive the ends of the manifolds 5. The division walls 6 across the headers compells the medium introduced into the headers to discharge through the openings 4 into the manifolds 5. The headers thus divided form the groups of manifolds into series of two forming a cross connection between the manifolds to allow for return circulation in the up and down movements of the cooling medium.

From Fig. 3 of the drawings, it will be apparent that the upper header possesses a pair of end chambers and a series of larger intermediate chambers, which latter correspond to the chambers of the lower header, shown in Fig. 4.

The manifolds consist of a section of tubing closed at the outer end and having a series of radiation tubes 7 fixed in a series of openings formed therein and communicating with a similar manifold at the other end. The top and bottom manifolds 5 are adapted to engage the groove formed around the lateral opening in the top and bottom headers. The radiation sections are arranged in groups of two on opposite sides of the headers and are held in this fixed position by the bolts 8 passing through the manifolds and the header, and having the nut 9 screwed on the ends outside the closed ends of the manifolds. The tension of the bolts compresses gaskets interposed between the ends of the manifold tubes and the bottom of the grooves formed around the openings in the headers.

To permit proper drainage of the whole radiator, the division walls 6 are provided with a small perforation 10. This perforation is not large enough to interfere with the forced circulation through the radiator, and is merely a precautionary measure to

permit the complete withdrawal of all the water or other circulating medium liable to burst the radiator by freezing when inactive.

5 A drainage cock of conventional form is preferably connected to the lower header as shown in Fig. 1.

In operation the cold circulating medium is pumped from the bottom of the reservoir 11, through the service cock 12 and the check 10 valve 13, by the pump 14, and forced through the pipe 15 into the water jackets of the engine cylinders 16. From the water jackets the liquid is discharged into the top header 1, and is distributed through the 15 openings 4 into the manifolds; thence down through the radiation tubes into the lower manifolds; thence into the chamber 17 of the lower header 1^a, from whence it passes out through the lower manifolds, upward 20 through the second series of radiation tubes, and into the top manifolds; from whence it is discharged into the second chamber 18 of the top header; from whence it is discharged 25 into the third sections of the radiator; continuing thus to pass upward and downward through the succeeding radiation tubes from one header to the other header until finally discharged from the last section back into the top header, from whence it is forced 30 through the pipe 19 back into the reservoir.

The radiator is inclosed within the sheathing 20 open at the rear and provided with the flanged circular opening 21, at the front. The fan 22 is adapted to rotate within this 35 opening and is mechanically driven from the engine shaft to cause a blast of air to circulate about the outer surfaces of the radiation tubes. The circulating system is provided with the sight glass 23 through 40 which the quantity and the condition of the circulating medium can be observed.

The multiplicity of parts comprising a radiator and the necessarily fragile nature of its attenuated radiation tubes, make it 45 necessary to provide convenient means for repairing leakages, caused by vibration and the rough usage incidental to this character of machinery. In the event of a leak occurring in any of the radiation sections the nuts can be removed from the bolts holding the 50 injured section in the assemblage, the section removed and a complete new section substituted with very little effort. If no new section is available the injured one can 55 be easily repaired when removed and as readily replaced. If one or more of the sections are damaged beyond repair, they can

be removed and dummy manifolds substituted in an emergency. The advantages of this unit section system are too obvious to 60 require extended description. The particular advantage of forcing the circulation upward and downward as before described from the rear forward, is that the whole body of circulating medium is compelled to 65 pass through all the tubes; in contradistinction to the common type of radiator, wherein the body of liquid may be disturbed by internal currents; the hot liquid seeking the line of least resistance, causing uneven distribution of heat and throwing undue stress upon certain portions of the radiation surface, while other portions of the mass lie 70 dead or trapped within the radiator. A further advantage of this arrangement of 75 the radiator and the novel circuit of the liquid is that the coldest liquid passes out of the radiator immediately behind the fan. By this method the coldest liquid is delivered to the water jackets and the greatest 80 heat in the radiator is at the rear from whence it is carried away by the fan blast; the extremes of temperature are avoided in any one set of the radiation tubes.

Having thus described this invention what 85 is claimed and desired to secure by Letters Patent is;

A radiator including an upper header having a series of large chambers and a pair of end chambers, stationary partitions separating the chambers, a lower header having a series of large chambers, stationary partitions separating said last named chambers, a pair of manifolds for each end chamber, two pairs of manifolds for each large chamber arranged one pair on each side thereof, and communicating therewith, each of said manifolds being of considerable length and being spaced apart throughout their lengths and being independent of each other, and a 90 plurality of series of vertical tubes, each series being composed of a multiplicity of tubes which connect the manifolds of the end chambers of the upper header to the outer ends of the chambers of the lower 95 header and also connect the manifolds at the alternate ends of the larger chambers of both headers.

In testimony whereof, I have hereunto set my hand this 3rd day of October, 1911. 110
BENJAMIN HOLT.
